UNITED STATES PATENT OFFICE

WILLIAM ROBERT OYSTON, OF PARKVILLE, VICTORIA, AUSTRALIA, ASSIGNOR TO CONTINUOUS GRAMOPHONES LIMITED, OF LONDON, ENGLAND, A BRITISH JOINT-STOCK COMPANY

NEEDLE CHANGING DEVICE

Original application filed March 12, 1928, Serial No. 260,378, and in Great Britain March 12, 1928. Divided and this application filed May 24, 1929. Serial No. 365,675.

This invention relates to an improved needle changing device for sound reproducing apparatus, more particularly talking machines of the magazine player type, said device being of the kind wherein the movement of the sound box or reproducer to and from a playing position also controls the automatic changing the needle.

The invention consists in a needle changing device for sound reproducing apparatus, more particularly automatic talking machines in which means are provided whereby the movement of the sound reproducer from a playing to a non-playing position produces the release of the used needle for discharge from its supporting housing, whereupon a new needle fed automatically from a magazine and substituted for the used needle is clamped in the housing during the return movement of the sound reproducer to playing position and prior to the engagement of the needle with the record to be played.

Means are also provided for supporting the new needle in its housing until clamped therein, said supporting means being brought into operative position by the needle clamping means after the used needle has been released and discharged.

The invention will now be described with reference to the accompanying drawings which illustrate, by way of example, the needle changing device according to the invention as applied to a talking machine wherein the records are played in a vertical position, that is to say, on edge. Such a talking machine is described and illustrated in detail in the specification of my pending application Serial No. 260,378, filed March 12th, 1928, of which this application is a division and in consequence thereof, only the essential parts of the talking machine necessary to illustrate the function of the device in accordance with this invention are shown in the accompanying drawings, in which:

Figure 1 is a perspective view of a talking machine sound box provided with needle clamping and releasing means.

Figures 2 and 3 are elevational views illus-

trating the sound box in a non-playing and playing position respectively.

Figure 4 is a detail perspective view of the needle housing and the members co-operating therewith to clamp and to release the 55 needle.

Figure 5 is a perspective view of the needle magazine.

Figure 6 is a sectional plan thereof.

Figure 7 is a sectional elevation on the 60 line 7—7 of Figure 6.

Figure 8 is a perspective view of the means for moving the sound box to and from a playing position and for simultaneously actuating the means controlling the supply of new 65 needles from the magazine.

Referring to the drawings, the stylus bar 1 of a loosely supported sound box 2 carries at its outer end an open ended housing 3 into which is led the free end of a flexible tubing 4 having its other end in communication with the needle magazine 5. Pivotal attached to the sound box 2 is an arm 6 having at its outer end a pivotal cradle 7 adapted to oscillate about its pivot against the tension of a 75 spring 8. When the sound box 2 is located in a journal or non-playing position, the cradle 7 is juxtaposed to the open end of the housing 3 (Figure 2), and upon a needle 9 passing downwardly through the tubing 4 so and into the housing 3, the pointed end of the needle rests in the cradle 7. Loosely supported by the sound box 2 is a finger 10 provided with lugs 11 and 12 and normally held at rest by a tension coil spring 13 which 85 causes the lug 12 to abut against a set screw 14 of the needle chute 15 when the sound box 2 is located in a non-playing position.

When the sound box 2 is being moved into a playing position the needle 9 is caused to 90 tilt, so that portions of its shank abut separate portions of the housing 3 and because the point of the needle rests in the cradle 7, the arm 6 will be caused to move together with the sound box. During such combined movement, the needle 9 contacts with the lug 11 thereby causing the finger 10 also to move with the sound box against the action of its coil spring 13, the tension of which spring 95 causes the lug 11 to hold the needle firmly in 100

position in the housing 3. As the movement of the sound box continues the arm 6 is stopped by contact with the record 16, and the continued movement of the sound box causes the needle 9 to oscillate the cradle 7 about its pivot against the tension of the spring 8 as shown in dotted lines in Figure 3, which pivotal movement enables the needle 9 to free itself from the cradle 7 and to move into operative contact with the playing surface of the record 16.

As the arm 6 is loosely mounted upon the sound box, the release of its cradle 7 from the needle 9 allows the said arm 6 to move out of contact with the record 16. When the sound box 2 is being returned to a non-playing position the lug 12 meets the set screw 14 of the needle chute 15 thereby preventing further movement of the finger 10, and thus, the continued movement of the sound box 2 releases the needle 9 from its engagement with the lug 11, so that the said needle will fall into the needle chute 15 after striking against the cradle 7. During the playing of the record 25 the pressure thereof on the needle 9 additionally ensures that the latter will be locked in the housing 3.

The needle magazine 5 (Figures 5, 6 and 7) is divided into two compartments 5¹ and 5², one for soft tone needles and the other for loud tone needles, which compartments are mounted upon a common inclined base plate 17 secured to a bracket 18 which is rigidly attached to a rod 19 firmly supported by a stationary part of the talking machine. The compartments 5¹ and 5² have a plurality of louvered partitions 20 adapted to prevent the needles from gathering at the delivery end of the compartments. In the bottom of the compartments 5¹ and 5² and slidably mounted on the base plate 17 are a pair of sliding plates 21 and 22 each having an opening 23 adapted to accommodate a single needle 9. Each of the openings 23 is adapted to register with separate openings 24 having V-shaped or tapered ends and provided in the base plate 17 in a position above chutes 25. Such chutes are rigidly attached to the base plate 17 and are open to the flexible tube 4 which constitutes the means of communication between the said chutes 25 and the housing 3 of the stylus bar 1. The openings 24 are shaped to ensure that the needles 9 entering such openings will pass into the chutes 25 in a point foremost position.

Sliding movement of the plates 21 and 22 agitates the needles 9 located in the compartments 5¹ and 5² so that such needles are regularly and evenly fed from the said compartments to the openings 23 and from thence to the openings 24.

The sliding plates 21 and 22 can be operated separately and selectively through a bell crank lever 26 slidably mounted on a rod 27 rigidly attached to the bracket 18; for this

purpose each sliding plate is provided with a recess 29 adapted to be separately engaged by the said lever 26. The engagement of the bell crank lever 26 with either of the recesses 29 is accomplished by manually sliding a transverse plate 30 provided with an opening 31 adapted to receive one limb of the bell crank lever 26. The transverse plate 30 can only be moved when the sound box 2 is in a playing position, as both the sliding plates 21 and 22 are then in a backward position.

The bell crank lever 26 is operated by a connecting rod 32 (Figure 8) resiliently connected to a radial arm 33 rigid with a shaft 34 adapted to be oscillated by any suitable means.

The shaft 34 is also adapted to effect the movement of the sound box 2 to and from a playing position, and for this purpose a bracket 35 (Figure 1) is rigidly attached to the sound box 2, which bracket is provided with an arm 36 to which one end of a connecting link 37 is pivotally attached while the other end of the said link is loosely supported in a jaw 38 (Figure 8) of a block 39 slidable on a fixed rod 40, which block is connected by a link 41 to a bell crank lever 42 rigidly connected to the oscillatory shaft 34.

Assuming that a needle 9 is positioned in the housing 3 and that the bell crank lever 26 has been manually moved to engage the recess 29 in the sliding plate 22, the operation of the device is as follows:—

When it is desired to play a record the shaft 34 is turned in the direction of the arrow (Figure 8) so that the bell crank lever 42 through the link 41 will cause the block 39 to slide outwardly on the rod 40 and thereby pull down the link 37 so as to turn the sound box 2 (with the needle in position) into engagement with the record to be played. During such movement of the sound box 2 the needle 9 will be firmly clamped in the housing 3 as hereinbefore described. The aforesaid movement of the shaft 34 not only moves the sound box 2 into a playing position but also causes its arm 33 to raise the connecting rod 32 so as to rock the bell crank lever 26 into the position shown in dotted lines in Figure 7, thereby drawing the slide 22 inwardly ready to receive a new needle in the slot 23.

The return movement of the sound box 2 to a non-playing position is effected by a return movement of the shaft 34 to its original position, which return movement of the shaft also causes the connecting rod 32 to pull down upon the bell crank lever 26 so as to push the slide 22 outwardly and deliver a new needle into the tube 4, which needle passes into the housing 3, from which the used needle has been discharged as hereinbefore described.

It will be realized that the device according to this invention is adaptable to talking machines generally, whether automatic or

non-automatic, and that the construction of the various elements constituting the device can be modified without departing from the scope of the appended claims.

What I claim is:

5 1. In a sound reproducing apparatus having a stylus-needle mounted on a sound reproducer movable from a playing to a non-playing position and vice versa, a needle changing device comprising means for clamping the needle in operative position, said clamping means being automatically released upon movement of said sound reproducer away from the playing position; means for feeding a fresh needle to said sound reproducer within reach of said clamping means, and means for temporarily supporting said fresh needle in position for engagement until engaged by said clamping means during the return movement of said sound reproducer to playing position.

2. In a sound reproducing apparatus having a stylus-needle mounted on a sound reproducer movable from a playing to a non-playing position and vice versa, the combination of a needle-housing, means for feeding fresh needles successively to said housing, means for clamping a needle in position in said housing, means for synchronizing the release of said clamping means with the movement of said sound reproducer away from the playing position, and means for synchronizing the feed of a fresh needle with the movement of said sound reproducer to non-playing position, said clamping means being automatically reengaged during movement of said sound reproducer back to the playing position.

3. In a talking machine having a stylus-needle mounted on a sound reproducer movable from a playing to a non-playing position and vice versa, the combination of a needle-housing secured to the actuator of said sound reproducer, a guide tube adapted to feed a fresh needle into said housing, a support for said fresh needle in said housing, a spring-operated clamp mounted upon said sound reproducer and adapted to engage the needle when supported in position in said housing, and means whereby the used needle is released from said clamp for discharge during movement of said sound reproducer away from the playing position, said means allowing the reengagement of said spring-operated clamp during the return movement of said sound reproducer.

4. In a talking machine having a sound reproducer movable from a playing to a non-playing position and vice versa, the combination of a needle-housing secured to the actuator of said sound reproducer, a guide tube adapted to feed a fresh needle into said housing, a cradle acting temporarily to support the fresh needle in said housing while said sound reproducer is in the non-playing posi-

tion, a spring-operated clamp mounted upon said sound reproducer and adapted to engage the needle when supported in position in said housing, and means whereby the used needle is released from said clamp for discharge during movement of said sound reproducer away from the playing position, said means allowing the reengagement of said spring-operated clamp during the return movement of said sound reproducer and before the fresh needle loses the support of said cradle.

5. In a talking machine having a stylus-needle mounted on a sound reproducer movable from a playing to a non-playing position and vice versa, a needle-changing device comprising spring-operated means for clamping a needle in operative position upon said sound reproducer, means for releasing said needle-clamping means during movement of said sound reproducer away from the playing position, a needle magazine, means for feeding fresh needles one at a time and always point-foremost from said magazine to within reach of said clamping means, the fresh needle being supplied after release of the used needle and in the non-playing position of said sound reproducer, and means allowing the engagement of said fresh needle by said clamping means during the return movement of said sound reproducer towards the playing position.

6. In a talking machine having a stylus-needle mounted on a sound reproducer movable from a playing to a non-playing position and vice versa, a needle-changing device comprising spring-operated means for clamping a needle in operative position, means for releasing said needle-clamping means during movement of said sound reproducer away from the playing position, a needle magazine adapted to contain fresh needles of different varieties, means for selecting the variety of needle supplied by said magazine, means for feeding the fresh needles of selected variety one at a time from said magazine to within reach of said clamping means, the fresh needle being supplied after release of the used needle and in the non-playing position of said sound reproducer, and means allowing the engagement of said fresh needle by said clamping means during the return movement of said sound reproducer towards the playing position.

7. In a talking machine having a stylus-needle mounted on a rotatable sound reproducer, a needle-changing device comprising means for clamping a needle in operative position, means for releasing said needle-clamping means during rotation of said sound reproducer in one direction, a needle-magazine, means for feeding fresh needles one at a time from said magazine to within reach of said clamping means, the fresh needle being supplied after release of the

used needle and about the end of said rotation of said sound reproducer, and means for temporarily supporting said fresh needle in operative position until engaged by said clamping means during rotation of said sound reproducer in the reverse direction.

8. In a talking machine having a sound box movable from a playing position to a non-playing position and vice versa, the combination of a needle-housing secured to the sound box actuator, a guide tube adapted to feed a fresh needle into said housing, an arm pivoted upon said sound box and adapted to contact with the record disk as said sound box approaches the playing position, a spring-controlled cradle pivoted upon said arm and adapted temporarily to support the fresh needle fed into said housing, a spring-operated clamp pivotally mounted upon said sound box and adapted to engage said needle while supported in said housing, and a fixed stop against which said clamp abuts as said sound box moves towards the non-playing position, said clamp being released for discharge of the used cradle by its abutment against said stop, and said cradle being rocked by the continued movement of the fresh needle clamped in said housing after the contact of said arm with the record disk, said arm then falling clear of said record disk.

9. In a sound reproducing apparatus having an automatic needle-changing device, a magazine adapted to contain a plurality of different varieties of fresh needles, means for selecting the variety of needle supplied by said magazine, and means for feeding needles of the selected variety one at a time and point-foremost from said magazine towards the sound reproducer, said feeding means operating for either of the selected varieties.

10. In a talking machine having an automatic needle-changing device, a magazine adapted to contain a plurality of different varieties of fresh needles, said magazine comprising a plurality of compartments for said different varieties, a slidable bottom plate in each of said compartments, each said slidable plate having an opening adapted to receive one needle at a time from the respective compartment, a base plate having openings adapted to register with the respective openings in said slidable plates, selective means for operating either of said slidable plates whereby to bring its opening from the interior of the respective magazine compartment into register with an opening in said base plate, and means for guiding the fresh needle from said last mentioned opening towards the sound reproducer.

11. In a talking machine having an automatic needle-changing device, a magazine adapted to contain two different varieties of fresh needles, said magazine comprising two

compartments for said different varieties, a slidable bottom plate in each of said compartments, each said slidable plate having an opening adapted to receive one needle at a time from the respective compartment, a base plate having openings adapted to register with the respective openings in said slidable plates, a bell crank lever adapted to operate either of said slidable plates whereby to bring its opening from the interior of the respective magazine compartment into register with one of the openings in said base plate, said slidable plates being formed with gaps on their contiguous edges and said bell crank lever being slidable on its axis for engaging one of its arms with either of said gaps, and a common chute adapted to receive the fresh needle delivered through either of the openings in said base plate and to guide it towards the sound reproducer.

12. In a talking machine having an automatic needle-changing device, a magazine adapted to contain two different varieties of fresh needles, said magazine comprising two compartments for said different varieties, a plurality of partitions across each of said compartments, said magazine being inclined to the horizontal and said partitions including louvers similarly inclined to the horizontal, a slidable bottom plate in each of said compartments, each said slidable plate having an opening adapted to receive one needle at a time from the respective compartment, a base plate having openings adapted to register with the respective openings in said slidable plates, a bell crank lever adapted to operate either of said slidable plates whereby to bring its opening from the interior of the respective magazine compartment into register with one of two openings in said base plate, said slidable plates being formed with gaps on their contiguous edges and said bell crank lever being slidable on its axis for engaging one of its arms with either of said gaps, and a manually operated selector device engaging said bell crank lever for sliding movement.

13. In an automatic talking machine having an oscillating shaft for controlling its operations, and having a needle-fitted sound reproducer movable from a playing to a non-playing position and vice versa in controlled relation to the movements of said oscillating shaft, an automatic needle-changing device which includes means for clamping a needle in operative position upon said sound reproducer, said clamping means being automatically released upon movement of said sound reproducer away from the playing position, a needle-magazine, means for feeding needles one at a time from said magazine to within reach of said clamping means, the fresh needle being supplied after release of the used needle, means for temporarily

supporting said fresh needle in operative position until engaged by said clamping means, and means for controlling the release and engagement of said clamping means and the operation of said feeding means in relation to the movements of said oscillating shaft.

In testimony whereof I hereunto affix my signature.
